UNITED STATES PATENT OFFICE.

KENNETH P. BEATTIE, OF HOPKINS, MICHIGAN, ASSIGNOR TO THE TAYLOR SMITH & TAYLOR COMPANY, OF EAST LIVERPOOL, OHIO.

DESIGN FOR A CASSEROLE OR SIMILAR ARTICLE.

Application filed September 10, 1925. Serial No. 14,741. Term of patent 3½ years.

To all whom it may concern:

Be it known that I, KENNETH P. BEATTIE, a citizen of the United States, residing at Hopkins, in the county of Allegan and State of Michigan, have invented a new, original, and ornamental Design for a Casserole or Similar Article, of which the following is a specification, reference being had to the accompanying drawing, forming part thereof. Fig. 1 is a side elevation of the casserole showing the new design. Fig. 2 is a plan view of said casserole. I claim:— The ornamental design for a casserole or similar article, as shown. KENNETH P. BEATTIE.
